United States Patent Office.

THOMAS J. SLOAN, OF NEW YORK, N. Y.

Letters Patent No. 77,114, dated April 21, 1868.

IMPROVEMENT IN OPERATING WINDOW-SHUTTERS.

The Schedule referred to in these Letters Patent and making part of the same.

TO ALL WHOM IT MAY CONCERN:

Be it known that I, THOMAS J. SLOAN, of New York, of New York county, in the State of New York, have invented certain new and useful Improvements in Apparatus for Opening and Closing Window-Blinds; and I do hereby declare that the following is a full and exact description thereof, reference being had to the accompanying drawings, making part of this application.

My invention relates to certain new and useful improvements in devices for opening and closing and locking in either position outside window-blinds.

Previous to my invention, several devices or mechanisms have been suggested and employed to accomplish the ends of my present invention, and Letters Patent have been granted to me for such devices.

The object of my present invention is to afford a simple, durable, and economic mechanism or device, by means of which any outside blind may be readily opened and closed, and fastened in either position, by simply turning a handle, arranged on the inner side of the window-frame; and also to so adapt and apply such a device that the blind can be unhung with the same facility as if mounted on ordinary hinges, and without in the least interfering with the operations of said device; and to these ends my invention consists in the employment, in combination with the toothed-hinge sector, driving-sector, and rotary shaft or rod, of a catch or bolt for retaining the driving-sector in different positions, and operated by a cam and spring, all as hereinafter more fully described.

And my invention further consists in the employment, in connection with the hinge-sector and its support, of a swinging pendant, so arranged over the hinge-sector that, when in its normal position, it securely retains the blind on its bearings (or hinges,) and when turned up will permit the ready removal of the blind, as will be presently more fully described.

To enable those skilled in the art to make and use my invention, I will proceed to describe it more fully, referring by letters to the accompanying drawings, making part of my application, and in which—

Figure 1 is an edge view of a window-frame and shutter, (the latter open,) hung thereto with my improved opening and closing-hinge device.

Figure 2 is an outside face view of the same, showing the blind closed, and

Figure 3 is section at the line *a a*, fig. 1.

In the several figures the same letters denote the same part of the apparatus.

A is the window-frame, and *B* an ordinary outside blind or shutter, which is hung near its upper end to the window-frame by means of the ordinary hinge, *C*, and near its lower end by one of my improved opening and closing-hinge devices or mechanisms, which consists of a metallic stand, *D*, secured to the outside of the window-frame, and carrying the working parts and a toothed-hinge sector-arm, *E*, secured to the shutter or blind, as clearly shown.

The stand *D* is formed with an arm, *e*, which serves as the supporting-shank of hinge-sector *f*, and also with another arm, *g*, in the extremity of which is arranged a pendant, *F*, the operation and advantage of which will be presently explained.

H is the rotary shaft, which passes through the window-frame in suitable bearings, the outer end taking a bearing in the arm *e*, and the inner end being provided with a handle, *I*, by means of which it is turned. On this shaft *H* is hung loosely the driving-sector gear, *K*, the hub of which has cut in it a longitudinal slot, *i*, through which protrudes the pin *l* from shaft *H*, in such a manner that when said shaft is turned in either direction, said pin will act as a clutch and carry the sector-gear *K*; and the hub of said sector-gear is also made with shoulders at *m*, which come against the catch-bar *n*, when down, as will be presently explained.

O is a cam, secured on shaft *H*, and so formed and arranged as to lift and hold up the catch-bar *n*. This bar *n* is arranged to slide vertically in ears or projecting lugs, *p p*, and is continually pressed down by a spiral spring, *S*.

The pendant *F* retains the blind on its hinges against any tendency to lift off, but is hung on a pivot, so

that it may be turned or swing upward, (as indicated by the red lines, fig. 1,) to permit the blind to be lifted off its hinges, in the usual manner, for any desired purpose.

The operation of the several parts already alluded to may be thus explained:

Supposing the shutter to be opened; (as seen at fig. 1,) it is retained in this position by the catch-bar *n*, which, being down past one of the shoulders *m* of the hub of gear *K*, prevents the said gear from turning, and thereby locks the shutter back. When the shutter is to be closed, the handle *I* is taken hold of and the shaft *H* rotated. By the rotation of said shaft, the cam *O* is turned and caused to lift the catch-bar *n*, thereby releasing the hub of gear *K*. As soon as this release is effected, the pin *l*, which turns with shaft *H*, comes against and carries along with it the hub of gear *K*, and the latter, driving the gear *f*, effects the turning of the blind on its pivots or hinges and closes it. As soon as the blind is quite closed, the spring-catch *n* shoots down past another shoulder *m*, and locks the blind in its closed position. When it is desired to reopen the blind, it is only necessary to rotate the shaft *H* in the opposite direction, when the locking-catch will be first raised, and the sector and gear then turned in the opposite directions to those just alluded to.

Having explained the construction and operation of my improved shutter-mechanism, so that one skilled in the art can make and use it, what I claim as new, and desire to secure by Letters Patent, is—

The employment, in combination with the gears *K*, *f*, and shaft *H*, of the retaining-catch bar *n*, and a cam, *O*, for lifting the same, the whole arranged to operate substantially as described for the purpose set forth.

I also claim the employment, in combination with the hinge-sector *f* and stand *D*, of a swinging or movable retaining-pendant, *F*, arranged to operate as described for the purpose set forth.

In testimony whereof, I have hereunto set my hand and seal, this 18th day of December, 1867.

THOS. J. SLOAN. [L. S.]
